UNITED STATES PATENT OFFICE.

OLIVER M. BABCOCK, OF CHICAGO, ILLINOIS, ASSIGNOR TO WIREBOUNDS PATENTS COMPANY, OF CHICAGO, ILLINOIS, A CORPORATION OF MAINE.

CRATE-MAKING MACHINE.

1,371,595.

Specification of Letters Patent. Patented Mar. 15, 1921.

Application filed March 6, 1917. Serial No. 152,482.

To all whom it may concern:

Be it known that I, OLIVER M. BABCOCK, a citizen of the United States, and a resident of Chicago, in the county of Cook and State 5 of Illinois, have invented an Improvement in Crate-Making Machines, of which the following description, in connection with the accompanying drawings, is a specification, like characters on the drawings representing 10 like parts.

This invention relates to improvements in the manufacture of crates from spaced slats and suitable reinforcing or stiffening means such, for instance, as cleats, parts of the 15 crate being bound one to another by wire or the like. The invention comprises mechanical means for making, or partially making such crates.

Prior to this invention box blanks comprising substantially continuous or imperforate sides wirebound together so as to be foldable into boxes, have been made by feeding into a fastener driving machine sheets 20 of veneer or the like, constituting the sides 25 of the box, and suitable cleats, together with wire for binding the sides together—the fastener driving instrumentalities being arranged to secure the sheets, cleats and wires in proper relationship to permit the side 30 sheets to be folded into box form. The present invention will be explained, for illustration, as embodied in a machine of this general type, but it is to be understood that the invention is not limited to such a machine. 35

The character of the invention may be readily understood by reference to an illustrative machine shown in the accompanying drawings, in which:

40 Figure 1 is a side elevation of a machine of the type referred to;

Fig. 2 is a partial section of the machine shown in Fig. 1 in a plane parallel with that of the sheet of Fig. 1;

45 Fig. 3 is a side elevation of a portion of the machine viewed from the side opposite that shown in Fig. 1, and the machine also being in the opposite phase of its motion;

Fig. 4 is a vertical detail section of the 50 line 4—4 of Fig. 1;

Fig. 5 is a fragmentary plan view of the parts shown in Fig. 4;

Fig. 6 is a modification of the arrangement shown in Fig. 4, as more fully explained hereinafter;

Fig. 7 is a fragmentary plan view of the parts shown in Fig. 6; and

Figs. 8, 9 and 10 are detached detail elevations of different forms of spacer blocks.

Referring to Fig. 1, a frame 1 carries 60 shafts 2 and 3, having journaled thereon respectively sprockets 5 and 6 for a chain 7. Said chain 7 is attached at 8 and 9 to a lug 10, depending from the carriage 11, mounted upon wheels 12 which run in suitable 65 guideways on the frame 1. The carriage 11 supports a fastener driving mechanism hereinafter referred to, and the movement of the carriage lengthwise the table 1 conveys said driving mechanism from one desired 70 driving position to another.

The work on which the fastener driving mechanism it to operate may be supported beneath the carriage 11 and between the sides of frame 1 (see Fig. 2) by suitable 75 feed chains 13 which conveniently have provision for relatively positioning the blank forming materials. Herein the chains 13 are trained over suitable sprockets 14 mounted on shaft 3 and sprockets 15 on a shaft 16 80 journaled in suitable brackets 17. The chains 13 are shown broken away in Fig. 1 and preferably extend to the right a sufficient distance to permit materials to be assembled thereon beyond the end of the 85 frame 1 while the driving mechanism is operating on those materials supported between the sides of the frame. There may be any suitable number of companion chains 13 to suit the characteristics of the particular 90 type of crate desired to be made, and several types of such coöperating chains are illustrated in Figs. 4 and 6 and will be fully explained hereinafter.

On the carriage 11 is mounted the motor 95 19 the rotor of which carries a pinion 20 which meshes with a gear 21 on the shaft of which is mounted a pulley 22. The pulley 22 is connected by belt 23 to a pulley 24 mounted on a shaft 25 carried by suitable 100 standards on the carriage 11. The hub or sleeve of the pulley 24 has also formed thereon a smaller pulley 26, adapted to be connected by belt 27 to the pulley 28 on shaft 29 journaled in the carriage 11. The belt 105 27, joining pulleys 26 and 28 may normally be somewhat loose and an idler 30 is provided which may be drawn into engagement with the belt by means of the hand lever 31 to tighten the same and thereby to drive the 110

pulley 28 from pulley 26. As seen in Fig. 2 shaft 29 has secured thereon pinions 32 adapted to mesh with racks 33 extending longitudinally in frame 1 of the machine. 5 It will be understood that if the belt 27 is tightened, rotation of the motor in a clockwise direction will drive the shaft 29 through the train of mechanism described in a counter-clockwise direction and thus 10 move the carriage 11 along the frame 1 toward the left viewing Figs. 1 and 2.

The pulleys 24 and 26 may be clutched to the shaft 25 to rotate the same therewith by means of a clutch 34 which may be controlled by a hand lever 35. The form of clutch is not herein illustrated in detail, but it may be of the well known type consisting of a semi-cylindrical rod fitting a semi-cylindrical groove in the shaft adapted when 15 turned on its axis to enter a semi-cylindrical groove in the hub of the pulleys. 20

In Fig. 2 there is shown on the shaft 25 eccentrics 36 which exemplify any practicable driving instrumentality for stapling 25 or other fastener driving mechanisms 37. The latter may be of any suitable or desired type, as, for instance, stapling mechanism already well-known in the art, and it is unnecessary to enter into a detailed description 30 thereof herein.

Referring now to Fig. 3, shaft 25 has mounted on one end thereof the crank disk 38 to which is attached the pitman or connecting rod 39 connected at its opposite end 35 to a pawl carrying lever 40 pivoted on the end of the pinion carrying shaft 29. Shaft 29 has a ratchet wheel 41 thereon and the lever 40 has a pawl 42 with a weighted end adapted to swing the same into coöperation 40 with the ratchet wheel. Mounted on the carriage 11 adjacent the pawl is a spring-catch 43 having a recess adapted to receive an arm 44 extending from the pawl and hold the same away from the ratchet 41 as illustrated 45 in Fig. 3. Brackets 45 and 46 are provided on the frame of the machine, having extensions adapted to strike the end of the pawl at the extremes of travel of the carriage 11. As illustrated in Fig. 3, the extension 50 on bracket 45 has just engaged the pawl, swung the same clockwise and pressed the arm 44 thereon into recess of spring-catch 43. The pawl is thus held free from the ratchet wheel. After the carriage has 55 traveled to the right, viewing Fig. 3, the extension on bracket 46 will engage the pawl, rock the same free of the spring-catch into position to engage the ratchet and drive the same in a counter-clockwise direction (viewing Fig. 3) as the shaft 25 turns. If the 60 pawl is in this operative position and the shaft 25 clutched to the driving pulley 24 it will be understood that the shaft 29 will be giving intermittent rotation and through

the pinions 32 will drive the carriage 11 65 step-by-step toward the left in Fig. 3.

The operation of the machine may now be understood. Suppose the carriage to be in the position shown in Figs. 1 and 2. The belt 27 is loose and the machine is ready to commence a stapling operation. If the clutch 34 be thrown in by means of the lever 35, the pawl 42 seen in Fig. 3 being released from catch 43 and in position to operate on the ratchet 41, the rotation of the shaft 25 75 will cause the carriage to be advanced step-by-step to the right, viewing Figs. 1 and 2. In the intervals between the steps, the stapling devices 37 will operate to apply staples to the work. Preferably the staples 80 are made to straddle suitable binding wires which may be led to work from holding reels, not shown, through guides 47 (Fig. 1). To halt the travel of the carriage and prevent it from running off the frame 1 a 85 lug 48 may be provided on the frame adapted to contact with an extension 49 from the clutch controlling lever 35 and so act to throw out the clutch when the carriage has reached an extreme right-hand position. 90 The action of the staplers and the movement of the carriage will be at once halted. The carriage will now be in the position shown in Fig. 3, and the extension on bracket 45 will have acted to throw pawl 42 clear of 95 its ratchet and into coöperation with the spring holding catch 43.

To return the carriage to initial position and at the same time to bring into place new work to be acted upon, the operator may 100 tighten the belt 27 by moving idler 30 through the hand lever 31. The motion of the pulley 24 which has been revolving idly on shaft 25 is therefore communicated to the pulley 28 to turn the pinions 29 seen in 105 Fig. 2 in a counter-clockwise direction and so to return the carriage to the position shown in Figs. 1 and 2. During this movement the pawl 42 (Fig. 3) is held by the catch 43, and the ratchet 41 is permitted to 110 revolve freely. The carriage may be stopped in the position shown in Figs. 1 and 2 by means of a lug 50 on the frame of the machine which will contact with an extension 51 on lever 31 and act to throw out the 115 idler 30 and loosen the belt 27. As the carriage stops, it is moved to the extreme right, viewing Fig. 3, and the extension on bracket 46 will contact with pawl 42, rock the same free of the holding catch and into position 120 to work on the ratchet on the next active movement of the carriage.

In the movement of the carriage from right to left viewing Fig. 1, the chain 7 will have been dragged around and the 125 sprockets 5 and 6 caused to turn in a counter-clockwise direction and through pawls 52 operating on ratchets 53 fast on shaft 3 the

sprockets 14 will have been rotated and the work carrying chains 13 will have been advanced to discharge at the left-hand end of the machine the work which has been operated on and to drag forward into position beneath the path of the carriage the new blank materials which have been positioned on the runs of the chains during the previous operation of the stapler mechanism. A retaining pawl 52^a and ratchet 53^a shown in Fig. 2 may be provided on shaft 3 to prevent retrograde movement of sprockets 14 in the working travel of carriage. The pawl and ratchet feed mechanism described is designed to advance the carriage a certain distance at each revolution of the shaft and to space the staples at regular intervals. It may be desired to vary the amount of travel of the carriage between any two successive stapling operations. This may be effected by means of the hand-lever 31, the pressing down of which tends to cause the carriage 11 to move in the direction opposite from that given it through the pawl and ratchet feed mechanism. The pressing down of this lever acts as a brake and permits the operator to take up the inertia imparted to the carriage after the pawl has ceased to operate on the ratchet. The operator may thus control the carriage practically at will.

For the purpose of adjusting the carriage manually to properly position the staplers with respect to the work, I here illustrate a ratchet feed wheel *a*, affixed to shaft 29, a lever *b* pivotally mounted on that shaft and a pawl *c* carried by said lever and controlled by an ordinary hand-grip such as illustrated, to bring it into co-operation with the ratchet *a* or throw it out of engagement. By vibrating the lever *b* while the belt 27 is slack, the carriage may be propelled independently of the motor and thus properly adjusted with reference to the work at the beginning of operations.

The illustrative type of machine hereinbefore described has many features of similarity to box making machines heretofore known in the art. By the mechanisms next to be described this type of machine is importantly modified to suit the peculiar characteristic problems of crate making, which are vitally different and substantially more difficult than those encountered in the making of the usual types of wirebound and like boxes.

One of the principal difficulties encountered in the manufacture of crates by machinery resides in the necessity for feeding to the fastening devices a plurality of separate sheets or slats for each side or other portion of the crate, and positioning the same as they are fed in proper relation to the reinforcements or cleats and to the wire or the like, and to the operating parts of the

machine. For instance, in making boxes of the type referred to, having substantially continuous and integral sheets to be connected in the operation of the machine and to have cleats attached thereto, these sheets are preferably spaced in substantial registration with the spaces between the cleats, and it is therefore a comparatively simple matter to provide co-operating cleat spacing and sheet spacing devices, which may be substantially unitary in construction. In crate making, however, slats require to be spaced practically independently of the cleat spacing, so far as concerns the spacing of slats between the extremities of the cleats. In other words, where two or more slats constitute a wall of the crate, these slats must be positioned properly in relation to the extremities of the cleats and must be additionally spaced in proper relation to each other between the extremities of the cleats. Furthermore, it is frequently desirable to provide cleats on opposite sides of the crate slats. The drawings illustrate practicable and successful apparatus for solving these and other problems involved in crate making. Other aspects of the invention pertain to the making of a gang of crates or boxes simultaneously.

To supply suitable spacing means for the slats on the crate, I preferably provide intercleat slat-spacing means, or, in other words, slat-positioning means out of the line of the cleats. In the embodiment of my invention here disclosed (see Fig. 4) I have done this by providing special chains 54, 55 and 56, having flanges or projections 57 to which may be attached spacers 58. The spacers may be of the form shown in Fig. 8 having jaws 59 adapted to fit over the flange 57 and be secured thereto by clamping screws 60. I prefer to provide three such spacers for each slat, as disclosed in Fig. 5, and I prefer to position two of these at the ends of one side of each slat, and a third on the opposite side of each slat in the center.

In making small crates, great economy is effected by using the entire width of the machine and so making several at the same time. In doing this, which I term multi-crate making, I have found it advantageous to use slats sufficiently long to make the number of crates which it is desired to make simultaneously, and later to saw them up into separate crate blanks. To perform this, I prefer to supply several sprockets such as 14 and 15, on the shafts 3 and 17 respectively, and over these run chains of different designs. In the embodiment here disclosed, I use seven chains of four different types. Of these, the chain 54 is provided with interiorly extending flanges or projections 57 and also a high side 61, and a low side 62, forming the channel or groove

63, into which the cleats 64 may be set end to end. The chain 56 is similar to chain 54, except that it is of the opposite hand. Chain 55 is similar to the chain 54, except that the sides are of equal height. The chains 65 are similar to the chain 55, but lack the projections 57. The chain 66 has no groove for containing a cleat, but is provided with a projection 67 adapted to hold a special attachment 68 for the purpose of extending up between the slats at intervals, to position laterally and longitudinally a cleat 69 to be attached to the top of the slats. This attachment may take the form shown in Fig. 9 having clamping jaws 70 and screws 71 adapted to secure the attachment to projection 67 of chain 66 and a body portion 72 offset from jaws 70 so as to be above and be supported by chain 66. This body portion 20 may have recesses 73 to receive the ends of successive cleats. The bottom of the groove of the chains 54 and 55, 56 and 65 preferably act as clenchers for the staples or other fastening instrumentalities which are driven by the fastener driving mechanism through the slat and the cleat. The top of the chain 66 also acts as a clencher for the fasteners which are driven through the cleat or batten 69 and the slat.

30 When the slats, cleats and battens have been properly stapled together, the blank may be completed either by readjusting the same machine or by using a second machine of the same type, carrying the chains 74 and 75 and the four chains 76 (see Fig. 6). The object of this second running is to attach the four battens 77. The chains 76 are similar to the chain 66 used on the first machine. To the projections 78 of these are fastened the attachments 79 which space laterally and longitudinally the battens 77. The members 79 chosen for illustration are shown in detail in Fig. 10. They are similar to the members 68 shown in Fig. 9 but the body portions thereof are channeled instead of being provided with recesses. After this second running is completed, the blanks are split by sawing the slats between the battens 77 and the cleats 64, and the batten 69 is split in two in this case. This divides the combined blank into six smaller crate blanks, each of which may be readily folded to form the four sides of the crate. In the claims I have referred to inter-cleat 55 slat spacing means. This, in this embodiment of my invention, refers to the spacers projecting up between the slats out of the line of the cleats. I have also referred to interslat cleat spacing means. This refers to the means projecting up between the slats to space superimposed cleats.

60 It is to be understood that the machine shown in the drawings and hereinbefore described for illustration, exemplifies merely

one practicable embodiment of the mechanical features of this invention, and that the invention is by no means limited to the specific type of machine described nor to the illustrative organization and mode of operation. On the contrary, both the mechanical and method features of the invention may be substantially varied within the scope of the subjoined claims. It is not indispensable that all the features of the invention be used conjointly, since they may be used to advantage separately, in various combinations and sub-combinations.

This application is a continuation of my application Serial No. 605,937, filed Feb. 1, 1911, in so far as it relates to matter common to the two cases.

Having now fully described one embodiment of my invention, what I desire to claim by Letters Patent is:

1. In a crate blank making machine, the combination of fastener applying mechanism; work supporting mechanism; means relatively to move the work supporting and fastener applying mechanisms to present different portions of the work in operative relation to the fastener applying mechanism; said work supporting mechanism comprising sub-slat cleat spacing means and superslat cleat spacing means, for producing endwise separation of the cleats below and above the slats respectively.

2. A wirebound crate blank making machine comprising a plurality of sub-slat cleat spacing means, and superslat cleat spacing means for the purpose of spacing the cleats below and above the slats of the blank.

3. A machine for making wire bound box-blanks by wiring together cleats and slats, comprising a traveling work-holder having super-slat cleat spacing means, devices to operate said work-holder, and means to apply binding wires to fasten the cleats and slats together.

4. A machine of the class described comprising, in combination, a stapling mechanism and a work holder adapted for relative movement, said work holder comprising a plurality of independent belts, certain thereof having means for positioning cleats and others having means for positioning cleats parallel to said first cleats and in a different horizontal plane.

5. A machine of the class described comprising work positioning chains having means for receiving cleats in end to end relation, and slat spacing members removably secured at selected points on the sides of said chains constructed and arranged to project above and laterally of the cleats to position the slats on the cleats in desired relationship.

6. A machine of the class described com-

- prising work positioning chains of channel form to receive cleats in longitudinal series, lateral flanges on said chains and slat spacing members having means for clamping 65
5 said members on said flanges at selected points and constructed and arranged to project above and laterally of said cleats to position the slats on the cleats in desired relationship.
- 10 7. A machine of the class described comprising work positioning chains having means for receiving cleats in end to end relation, lateral flanges on said chains and slat spacing members having means for 70
15 clamping said members on said flanges at selected points and constructed and arranged to project above and laterally of said cleats to space and hold the slats in desired relationship on the cleats.
- 20 8. A machine of the class described comprising work positioning chains of channel form to receive cleats in longitudinal series, and slat spacing members removably secured at selected points on the sides of said 75
25 chains and constructed and arranged to project above and laterally of the cleats to space the slats on said cleats.
9. A machine of the class described comprising relatively movable stapling mechanism and work holding mechanism, said work holding mechanism comprising endless chains having means for carrying forward cleats in end to end relation for operation of said mechanism thereon, and slat spacing members constructed and arranged for attachment to said chains at chosen locations along their length to project laterally of and above such cleats. 85
30
35
10. A machine of the class described comprising relatively movable stapling mechanism and work holding mechanism, said work holding mechanism comprising endless chains having means for carrying forward cleats in end to end relation for operation of said mechanism thereon, and slat spacing members having jaws adapted to receive and clamp on said chains at variably selected points and body portions projecting laterally of and above such cleats to 90
40
45
50 position the slats thereon.
11. A machine of the class described comprising feed chains being adapted to receive and position sub-cleats and one or more of said chains having members attached thereto having body portions overlying said chains and formed to receive and position super-cleats. 100
55
60
12. A machine for use in making wire-bound crates comprising, in combination, fastener-setting and binding-wire applying mechanism; work-positioning means for receiving and positioning cleats and slats, including devices arranged to project above the slats to position cleats thereon and hold 105
110
115
120
125
them against lateral or longitudinal displacement; and means to cause relative progression between the fastener-setting mechanism and the work. 65
13. A machine for use in making wire-bound crates comprising, in combination, fastener-setting mechanism; work-positioning means for receiving and positioning cleats and slats, including devices for positioning slats on sub-cleats, and other devices arranged to project above the slats and 70
75 position super-cleats thereon; and means to cause relative progression between the fastener-setting mechanism and the work.
14. A machine of the class described comprising endless work-supporting chains, a mechanism for operating on the work and reciprocable horizontally thereover, and means to drive said chains from said mechanism on its motion in one direction. 80
15. A machine of the class described comprising an endless work supporting device trained over sprockets, a mechanism for operating on the work and reciprocable horizontally thereover, a chain attached to said mechanism and trained over sprockets, and means to drive said first mentioned sprockets from the revolution of said chain in one direction. 85
90
16. A machine for use in making wire-bound cleat-reinforced crates, comprising, in combination, mechanism to secure binding wire to cleats and slats in crate-side forming assembly; and work-controlling means determining such assembly, including means for positioning the slats in spaced relationship on the cleats and at selected distances short of the ends thereof during the action of said mechanism. 95
100
17. A machine for use in making wire-bound cleat-reinforced crates, comprising, in combination, means for securing together with binding wires assembled cleats and slatted side material for a plurality of crate sections; and work-controlling means for determining, during the operation of wiring 105
110
115
120
125 and securing the materials together, relative positions of cleats and slats to form foldably related crate sections having a plurality of spaced slats on an individual section.
18. A machine for use in making wire-bound cleat-reinforced crates comprising, in combination, mechanism to fasten wires to assembled crate sections and secure the wooden parts thereof together; and work-presenting means constructed and arranged for relatively positioning cleats and a plurality of spaced slats for an individual section during such operation. 115
120
125
19. A machine for use in making wire-bound cleat-reinforced crates comprising, in combination, work-controlling means for positioning cleats and slats for a plurality of crate sections in coöperative foldable rela-

- tionship, including means for positioning a plurality of spaced slats for an individual section; and mechanism for foldably connecting said sections.
- 5 20. A machine for use in making wire-bound crates having slatted side material and reinforcing cleats, comprising work-controlling means for a plurality of separate sections of slats and cleats including 10 means to position the slats of individual and adjacent sections relative to the cleats and to each other, and means to secure binding wires to and the cleats and slats of the respective sections together.
- 15 21. A machine for use in making wire-bound crates having slatted side material and reinforcing cleats, comprising work-controlling means for a plurality of separate sections of slats and cleats including 20 means to position the slats of individual and adjacent sections relative to the cleats and to each other, and means to secure the cleats and slats of the respective sections together and connect the sections with binding wires.
- 25 22. A machine for use in making wire-bound crates comprising, in combination, means for supporting cleats in longitudinal succession; means for positioning a succession of slats thereon in spaced relation crosswise of the cleats and at selected distances short of the cleat ends; and mechanism for wiring together the slats and fastening the slats to the cleats.
- 30 23. A machine for use in making wire-bound crates having cleats and slatted side material which comprises, in combination, means to secure binding wire to crate parts; means to cause relative progression between said securing means and the crate parts; and means to position slats on a cleat in desired spaced relationship to each other and the cleats.
- 35 24. In a machine for use in making crates having a plurality of separate sections of slatted side material interposed between interior and exterior cleats, work-controlling means for said cleats and slats including means to position the slats between said cleats in desired spaced relationship.
- 40 25. In a machine for use in making crates having a plurality of separate sections of slatted side material and interior and exterior cleats, work-controlling means for said cleats and slats including means to position said exterior cleats relative to the interior cleats and slats.
- 45 26. A machine for use in making wire-bound cleat-reinforced boxes comprising, in combination, fastener-setting mechanism for applying binding wire to assembled box parts; and work-controlling means for determining, during the wiring operation, the relative positions of a plurality of pieces of side material on a single cleat.
- 50 27. A machine for use in making wire-bound cleat-reinforced crates or boxes comprising, in combination, means to position a plurality of pieces of side material in spaced relationship on individual cleats; and means for wiring and securing the materials together.
- 55 28. A machine for use in making wire-bound boxes comprising, in combination, fastener setting mechanism for securing binding wire to cleats and spaced slats; work-positioning means constructed and arranged to receive cleats and a plurality of spaced slats on each cleat and hold the same against lateral or longitudinal displacement; and means for causing relative progression between said mechanism and the work.
- 60 29. A machine for use in making wire-bound cleat-reinforced crates comprising, in combination, means to receive and position sets of cleats for a plurality of crates side by side; means to receive and space a plurality of slats on each of said cleats; and means to secure said cleats and slats together.
- 65 30. A machine for use in making wire-bound cleat-reinforced crates comprising, in combination, means to receive and position in end-to-end spaced relationship a plurality of rows of cleats for a plurality of crates; means for positioning a plurality of slats on each of said cleats relatively to each other and the cleats; and means for securing the slats to the cleats.
- 70 31. A machine for use in making wire-bound cleat-reinforced boxes comprising, in combination, a work support; fastener-setting and binding-wire-applying mechanism; means to space cleats; separate means for spacing side material on cleats; and means to cause relative progression between said mechanism and the work.
- 75 32. A machine for use in making wire-bound cleat-reinforced crates comprising, in combination, fastener-setting and binding-wire-applying mechanism; means to position cleats; adjustable means for positioning side material on a cleat at a selected distance from the cleat end; and means to cause relative progression between said mechanism and the work.
- 80 33. A machine for use in making wire-bound cleat-reinforced crates comprising, in combination, fastener-setting and binding-wire-applying mechanism; means to position cleats; adjustable means for positioning a plurality of slats on a cleat at selected distances from each other and the cleat ends; and means to cause relative progression between said mechanism and the work.
- 85 34. A machine for use in making wire-bound cleat-reinforced crates comprising, in combination, fastener-setting and bind-

ing-wire-applying mechanism; work-controlling means for positioning materials for a crate side, including means for positioning side material on a cleat at a selected distance short of the cleat end; and means to cause relative progression between said mechanism and the work.

35. A machine for use in making wire-bound cleat-reinforced crates comprising, in combination, fastener-setting and binding-wire-applying mechanism; work-controlling means for positioning material for a crate side, including means for positioning a slat on a cleat with its edges selected distances short of the ends of the cleat.

36. A machine for use in making wire-bound cleat-reinforced crates comprising, in combination, fastener-setting and binding-wire-applying mechanism; work-controlling means for positioning materials for a crate side, including means for positioning a plurality of slats on a cleat with their edges located at selected distances from the cleat ends and from each other, and means to cause relative progression between said mechanism and the work.

37. A machine for use in making wire-bound crates or boxes having cleats and side material comprising, in combination, means to apply binding wire to the work; means to cause relative progression between the binding-wire-applying means and the work; and work-controlling means including removable devices for spacing a sheet of side material a selected distance short of a cleat end.

38. A machine for use in making wire-bound crates or boxes having cleats and side material comprising, in combination, means to apply binding wire to the work; means to cause relative progression between the binding-wire-applying means and the work; and

work-controlling means including removable devices for selectively spacing a plurality of sheets of side material on a cleat. 45

39. A machine for use in making wire-bound cleat-reinforcing boxes comprising, in combination, endless work-forwarding means; means to apply binding wire to the box parts; means to cause relative progression between the binding-wire-applying means and the box parts; means detachably secured to the work-forwarding means at selected points to position cleats; and means detachably secured to the work-forwarding means at selected points intermediate the cleat-positioning means for spacing side material. 55

40. In a box blank machine, the combination of a cleat guide, spacing blocks for insertion between cleats, separate and independent sheet-spacing devices, and a common means for advancing said blocks; devices and associated work. 60

41. A machine of the class described comprising, in combination, mechanism for fastening together the cleats and side material of assembled box or crate sections and to secure binding wire thereto; and means for presenting such sections thereto with the parts in proper relationship, comprising separate and independent cleat and sheet forwarding devices, and a common actuating means for synchronously advancing said cleat and sheet forwarding devices. 65 75

42. A machine of the class described having, in combination, cleat-feeding means; separate and independent feeding means for side material associated with cleats; and a common actuating means for operating them synchronously. 80

In testimony whereof, I have signed my name to this specification.

OLIVER M. BABCOCK.
